AUTOMATIC LIGHTER

Harold A. Mantz, Milwaukee, Wis., assignor to
Milwaukee Gas Specialty Company, Milwaukee,
Wis., a corporation of Wisconsin

Application May 17, 1934, Serial No. 726,078

12 Claims. (Cl. 158—115)

This invention relates to automatic lighters, and is more particularly directed to automatic lighters employed in connection with domestic gas ranges, gas burners, hot water heaters and the like, for igniting the main burner or burners thereof, and for assuring reignition of the main burner flame if it is accidentally extinguished.

5 The present invention, in its preferred embodiment, provides a constantly burning pilot flame which is capable of igniting gas conducted to it through tube means leading from the various burners, and which ignited gas is then flashed back through the tube means to ignite the burner or burners which may be opened.

10 In the recent development of gas ranges and the like, clock or automatic control of the burners, to turn them off or on, has been found desirable in a number of instances. If the pilot flame fails to ignite a burner when it is turned on manually, some slight inconvenience results, but no serious difficulties arise. However, with the automatically controlled type of device, the failure of a pilot flame becomes of the utmost importance, and distinctly serious danger may 15 result from such failure, even though the appliance is equipped with a safety device that prevents the gas being turned on if the pilot flame is extinguished.

20 Failures of pilot flames have been found to be due largely to deposits of gum-like material on the needle or metering valves. Upon study of this phenomena, it has been found that this gum-like material floats along in the gas in minute particles, and passes through the mains 25 and meters and is consumed in the flame at the point where the gas is burned. However, these vapor-phase gums, so-called because the reaction of which they are a product takes place within the gas itself, and not necessarily at the point of manufacture, are not harmful as far 30 as the quality of the gas is concerned, but are distinctly objectionable because of the stoppage 35 of gas flow through metering valves, thermostatically controlled valves, and other places 40 where the gas passage is restricted, principally 45 at pilot valves and the like.

I have found that the provision of a novel type of pilot burner construction, as disclosed in the present invention, results in entire elimination of any tendency of these gum-like materials to deposit in the restricted valved passageway leading to a pilot tip or the like.

50 Thus, in the present invention, I have provided a porous ceramic pilot tip which allows 55 gas to leak therethrough about the entire ex-

posed surface of the tip, whereby the pilot flame entirely surrounds the tip and raises the temperature of the tip and its associated support to a point substantially above the vaporizing temperature of the gum particles which are in suspension in the gas stream, consequently preventing deposition of such materials in the restricted valved passageways.

5 Another object attained by the present invention is the maintenance of a highly efficient 10 and stable pilot flame which, due to the fact that it completely surrounds the pilot tip, is not liable to be extinguished by air drafts, gusts of wind or the like, since, although the flame may be extinguished on the windward side of 15 the tip, it tenaciously maintains itself on the leeward side thereof, and is therefore not readily extinguished.

In conjunction with this latter feature, and 20 because of the stability of the pilot flame due to this particular tip construction, it is possible to so ventilate the hood surrounding the pilot tip as to allow all the products of combustion to escape readily from the hood, resulting in a 25 minimum production of carbon monoxide and a 30 more positive operation of the lighter under adverse conditions.

Other objects and advantages of the present 35 invention, such as its simplicity of design and construction, will more readily appear from the 40 following detailed description which, taken in conjunction with the accompanying drawing, will disclose to those skilled in the art the 45 particular construction and operation of a preferred form of the present invention.

In the drawing:

Figure 1 is a vertical sectional view through a pilot lighter constructed in accordance with the teachings of the present invention;

Figure 2 is a plan view of a portion of the 40 structure shown in Figure 1;

Figure 3 is a detail elevational view of a modified form of pilot tip; and

Figure 4 is a sectional elevational view of a modified pilot lighter construction.

45 Referring now in detail to the drawing, in Figure 1 I have indicated a main burner 5, such as an open top burner for a domestic gas range, or a burner for a hot water heater or the like, which is provided with a plurality of burner 50 ports 6. Extending into the interior of the burner 5 and communicating therewith is a burner tip member 7, having the internal passageway 8 communicating with the interior of the burner 5, and having a laterally directed 55

passageway 9 communicating therewith. The tip 7 may be threaded or otherwise secured in the burner 5.

Supported upon the burner 5 and maintained in position by the tip member 7 is a lighter tube 10 which has the extending portion thereof, indicated at 11, secured beneath the tip 7, and which is provided with a cut-away portion 12, adapted to provide for projection of a lighting 10 flame from the tube 10 across the ports 6.

The tube 10, at its opposite end, is telescopically engaged by a second tube member 13, which extends axially thereof into a centrally located hood 14, in the present embodiment, in 15 which the lighter structure shown is applied to a domestic gas range having a plurality of burners 5. The tube or conduit 13 enters through a suitable opening in the hood 14, its inner end being crimped, as shown at 15, for 20 the purpose of non-rotatively securing it within the hood. The hood is composed of a substantially hemispherical portion 14 and a lower cup-shaped portion 16, the two portions having co-25 operating cut-away openings for receiving the ends of the tubes 13. The inner ends of the tubes 13 extend into and adjacent a pilot flame indicated at 17.

The pilot hood, comprising the members 14 and 16, which have telescoping engagement, is 30 provided with a plurality of inlet openings located in the base thereof, and with a centrally located flue opening or outlet 20. The lower portion 16 of the hood is supported upon a pilot tip support 22, and is maintained thereon by 35 means of a supporting nut 23 threaded over the lower extending portion 24 of the support 22.

The upper end of the support 22 is provided with an opening 25, and the defining cylindrical 40 wall of this opening is cut away, as shown at 26, to form an annular groove therein. Disposed within the recess 25 is a porous ceramic pilot tip 27 which is substantially cup-shaped in form, and which has its open end disposed within the 45 recess 25. Suitable cementitious material may be provided in the annular groove 26 for securing the pilot tip 27 within the recess 25, and the lower end of the recess is counterbored, as shown at 28, to provide a valved passageway leading 50 into the valve chamber 29 formed within the support 22.

The support 22 is provided with a laterally extending threaded bore receiving the lighter tube 30 in threaded engagement therewith, the tube 30 being threaded into a suitable coupling 55 member 31 extending into the interior of a gas manifold 32. The tube 30 thus provides a rigid support for the pilot tip support 22 and therefore also supports the hood 14 and the inner adjacent ends of the lighter tubes 13.

Threaded centrally into the pilot tip support 22, and extending upwardly from the lower end thereof, is a metering valve member 33 having the conically formed valve portion 34 cooperating 60 with the restriction or valve seat 28 for metering the flow of fuel through the tube 30 into the porous tip 27. The metering valve 33 is provided with a knurled outer end indicated at 65 35, providing for manual adjustment of the same, and suitable packing 36 is disposed within 70 a recess at the lower end of the pilot tip support 22 and is maintained in position by means of a spring member 37 biased between a suitable washer 38 bearing against the packing 36 and the upper surface of the knurled head 35 of 75 the metering valve 33. The metering valve is

rotatable to secure any desired flow of fuel from the lighter tube 30 into the interior of the pilot tip 27.

Referring to Figures 3 and 4, substantially the same construction is shown, except that in this embodiment the pilot tip support 22' is provided at its upper end portion with a cap member or bushing 40 threaded over an extending portion 41 of the pilot tip support 22'. The bushing 40 is provided with a radially inwardly extending 10 flanged portion 42 defining an opening cooperating with the valve opening controlled by the metering valve 33, and is also provided with an annular groove 43 corresponding to the groove 26 of the embodiment shown in Figures 1 and 2 15 for providing means for cementing the pilot tip 27 in position. However, in this modification the pilot tip and cap member 40 are removable from the pilot tip support for inspection, replacement, or repair. The operation, however, 20 is identical, and it is believed that a description of the operation in the embodiment shown in Figure 1 will suffice for the purposes of the present disclosure.

In Figure 1, the gas from the manifold 32, 25 carrying the suspended vapor-phase gums therein, passes through the lighter tube 30 and into the valve passageway or chamber 29. From the chamber 29 the gas flows through the restricted 30 passageway 28, controlled by the valve portion 34 of metering valve 33, and into the interior of the porous tip 27.

Due to the porosity of this tip, the gas then filters through the porous wall thereof and burns in a flame completely surrounding the tip 27, 35 thereby raising the temperature of the tip to a relatively high degree. The heat generated by the flame which completely surrounds the pilot tip 27, is transmitted to the pilot tip support 22, 40 since this material is formed of bronze or the like, and is readily conductive of heat, and the tip support 22 is therefore heated to relatively 45 the same temperature about a zone adjacent the tip 27. This temperature, I have found, is substantially above the vaporizing temperature of 50 the gum materials suspended in the gas, and therefore vaporizes any of such materials as they pass into the valve chamber 29. This effectively prevents clogging or stopping of the gas flow through the metered passageway 28, and thereby 55 provides a positive and reliable pilot flame tip.

When the gas supply to the burner 5 is opened, gas from the manifold 32 is admitted to the interior of the burner 5, and a portion thereof passes through the passageways 8 and 9 of the 55 tip 7 into the tube 10, and, due to the pressure thereof, is forced through the tube 10 and tube 13 into proximity to the pilot flame 17. This gas is ignited by the pilot flame 17, and is then flashed back through the tubes 13 and 10 over 60 the burner ports 6, igniting the same and thereby providing for ignition of the burner. Furthermore, upon accidental extinguishment of the burner flame, gas issuing from the tip 7 will 65 again serve to reignite the burner in the manner just described.

Due to the fact that the tip 27 is porous, any draft or sudden gust of air which would tend to extinguish the flame at one side of the tip will not extinguish the entire pilot flame, since it will 70 tenaciously maintain itself burning upon the leeward side of the tip, due to the fact that the ceramic material is substantially uniformly porous, and consequently a relatively stable and reliable pilot flame is maintained at all times. 75

Also, due to the fact that the pilot flame 17 cannot be readily extinguished by gusts of wind or the like, it is possible to provide relatively large openings 19 and 20 to provide for rapid circulation of air through the hood formed by the members 14 and 16, and consequently the hood is ventilated to such a degree as to allow all products of combustion to escape quickly therefrom, resulting in a minimum production 10 of carbon monoxide within the hood. This is of distinct advantage and provides a more positive operation of the lighter under adverse conditions, due to the fact that a uniform, well-burning pilot flame is provided at all times.

15 It is therefore apparent that I have provided an effective means for preventing deposition of these gum-like materials in a restricted gas passageway, and further, at the same time, have produced a more efficient and stable pilot lighter than heretofore possible, due to the provision of a porous ceramic tip which is capable of being heated to a relatively high temperature by the pilot flame produced by the gas filtering therethrough, and which is capable of transmitting 20 this heat to the metallic material surrounding the restricted valved passageway. Also, the present type of pilot lighter is not subjected to extinguishment by sudden drafts of air or the like.

30 I do not intend to limit myself to the exact details of construction which I have shown in the application of the present invention to a pilot tip, but only as defined by the scope and spirit of the appended claims.

35 I claim:

1. In combination a pilot tip formed of highly porous refractory material presenting innumerable relatively fine pores therethrough and an inlet for supplying to said tip gas in quantity only sufficient to maintain a relatively restricted constantly burning pilot flame externally of the tip.

40 2. In combination, a pilot tip formed of highly porous refractory material presenting innumerable relatively fine pores therethrough, a support for said tip, said support having a restricted passageway for supplying to said tip gas in quantity only sufficient to maintain a relatively restricted constantly burning pilot flame externally of the tip.

45 3. In combination a pilot tip formed of highly porous refractory material presenting innumerable relatively fine pores therethrough, an inlet for supplying to said tip gas in quantity only sufficient to maintain a relatively restricted constantly burning pilot flame externally of the tip, and means disposed in relatively close proximity to the tip for adjusting the flow of gas 50 to said tip.

55 4. In combination, an inverted cup-shaped pilot tip formed of highly porous refractory material presenting innumerable relatively fine pores therethrough, a support for said tip, said support having a restricted passageway for supplying to said tip gas in quantity only sufficient to maintain a relatively restricted constantly burning pilot flame externally of the tip, said passageway being coaxial with the tip and 60 opening upwardly directly into the tip, and a metering valve disposed beneath said passageway and cooperable therewith, said valve having an upwardly directed tapered end coaxial with 65 said passageway.

70 5. In combination, a pilot device comprising

a tip part having innumerable relatively fine pores for producing with a relatively restricted supply of gas a constant external pilot flame supplied with gas over substantially the entire surface of said tip part whereby to raise with the restricted pilot supply of gas the temperature of the tip part above the vaporizing temperature of the gum particles in the gas and to maintain the flame against being extinguished by gusts of air.

5

6. In combination, a pilot device comprising a tip part having innumerable relatively fine pores therethrough, and a support for said tip part, said support having a restricted passageway for supplying to said tip part gas in quantity only sufficient to maintain a relatively restricted constantly burning pilot flame externally of the tip part.

10

7. In combination, a pilot device comprising a tip part having innumerable relatively fine pores therethrough, a support for said tip part, said support having a restricted passageway for supplying to said tip part gas in quantity only sufficient to maintain a relatively restricted constantly burning pilot flame externally of the tip part, and valve means disposed adjacent the tip support for adjusting the flow of gas to said tip.

15

8. In a domestic gas range, the combination with a burner of a structure providing a pilot flame for igniting said burner, said structure comprising a pilot tip formed of highly porous refractory material presenting innumerable relatively fine pores therethrough, an inlet for supplying to said tip gas in quantity only sufficient to maintain a relatively restricted constantly burning pilot flame externally of the tip, and means adapted for supplying to said tip gas free of air and having suspended vapor-phase gum residues therein.

20

9. In combination, a pilot tip support having a recess in its upper end, a pilot tip cemented in said recess, said tip being formed of highly porous refractory material presenting innumerable relatively fine pores therethrough, said support having a restricted passageway for supplying to said tip gas in quantity only sufficient to maintain a relatively restricted constantly burning pilot flame externally of the tip, and a tube connected with said tip support and adapted for supplying a gaseous fuel having suspended vapor-phase gum residues therein.

25

10. In combination, a pilot device comprising a tip part having innumerable relatively fine pores for producing, with a relatively restricted supply of gas, an external pilot flame supplied with gas over substantially the entire surface of said tip part, and means for supplying to said tip part gas in quantity only sufficient to maintain a relatively restricted pilot flame at the tip.

30

11. In combination, gas supply means and a pilot lighter tip having innumerable relatively fine pores for producing with a relatively restricted amount of gas an external pilot flame supplied with gas over substantially the entire pilot flame surface of the tip, said tip having restricted communication with said gas supply means whereby the amount of gas issuing from said innumerable relatively fine pores is only sufficient to maintain a relatively restricted pilot flame at the tip.

35

12. In combination, gas supply means, a pilot lighter tip having innumerable relatively fine

40

45

50

55

60

65

70

75

pores for producing with a relatively restricted amount of gas an external pilot flame supplied with gas over substantially the entire pilot flame surface of the tip, said tip having restricted communication with said gas supply means whereby the amount of gas issuing from said

innumerable relatively fine pores is only sufficient to maintain a relatively restricted pilot flame at the tip, and means for adjusting the flow of gas to said tip.

HAROLD A. MANTZ.
